US0D1016475S

(12) **United States Design Patent** (10) Patent No.: **US D1,016,475 S**
(45) Date of Patent: ** Mar. 5, 2024

(54) **HANDBAG**

(71) Applicant: **Hongge Zhang**, Mianyang (CN)

(72) Inventor: **Hongge Zhang**, Mianyang (CN)

(**) Term: **15 Years**

(21) Appl. No.: **35/516,214**

(22) Filed: **Jan. 13, 2023**

(80) **Hague Agreement Data**

Int. Filing Date: **Jan. 13, 2023**

Int. Reg. No.: **DM/226407**

Int. Reg. Date: **Jan. 13, 2023**

Int. Reg. Pub. Date: **Feb. 10, 2023**

(30) **Foreign Application Priority Data**

Jul. 19, 2022 (CN) 202230461305.8

(51) **LOC (14) Cl.** **03-01**

(52) **U.S. Cl.**

USPC **D3/232**

(58) **Field of Classification Search**

Primary Examiner — Steven J Czyz

(57) **CLAIM**

The ornamental design for a handbag, as shown and described.

DESCRIPTION

1. Handbag

1.1 : Perspective

1.2 : Perspective

1.3 : Front

1.4 : Back

1.5 : Left

1.6 : Right

1.7 : Top

1.8 : Bottom

1.9 : Cross-sectional view taken along the line 9-9 in fig. 1.3

The portions shown by means of broken lines in the reproductions are not part of the claimed design; the symbolic break line 9-9 in fig. 1.3 is for the purpose of depicting the cross-section view and form no part of the claimed design; other non-solid lines are the surface shading lines provided only to indicate the character and/or any contour, and/or curvature of the surface of the article and do not represent the surface decoration.

1 Claim, 9 Drawing Sheets
